BOBBIN CLUTCH FOR SPINDLE BLADES

Thomas J. Risk, Central Falls, R. I.

Application March 20, 1944, Serial No. 527,362

7 Claims. (Cl. 242—46.4)

This invention relates to a spindle blade, more particularly to a clutch for engaging and holding a bobbin on the blade for rotation with the blade.

Frequently means for retaining the bobbin on the spindle blade is carried by the bobbin. This requires a large number of means, one for each of the bobbins in use. It is known that wood bobbins swell or contract due to moisture conditions and do not uniformly fit a blade to be driven thereby. Certain metal linings are sometimes provided and at times clutches have been provided, but in such instances soon become foul with lint or dirt and cease to function, making a very awkward condition and requiring cleaning in order that they may again have a resilient grip upon the bobbin.

One of the objects of this invention is to provide a bobbin clutch on a spindle blade which will be so constructed that dirt cannot readily get into and foul the operation of the clutch.

Another object of the invention is to provide a clutch which will be extremely simple and require a minimum of operations for making or assembling the same on the blade.

Another object of this invention is to provide a clutch which will be so arranged that the bobbin will be accurately lined up with the blade when positioned thereon, that the bobbin may rotate at high speeds without any eccentricity, wobble or play which causes wear upon the spindle.

Another object of the invention is to provide a clutch which will vary to the size of the various bobbins which may be utilized regardless of their condition of swelling or drying out due to variation in moisture conditions.

With these and other objects in view, the invention consists of certain novel features of construction, as will be more fully described and particularly pointed out in the appended claims.

In the accompanying drawing:

Fig. 1 is a sectional view showing a blade with a bobbin mounted thereon and my improved clutch in position;

Fig. 2 is a sectional view on a larger scale of a fragmental portion of the whorl, blade, and clutch;

Fig. 3 is a view similar to Fig. 2 illustrating a bobbin as positioned on the blade which is equipped with the clutch;

Fig. 4 is a sectional view on line 4—4 of Fig. 2;

Fig. 5 is a perspective view of one of the nesting clutch members;

Fig. 6 is a perspective view of a modified form of clutch member in that the split is arranged helically instead of longitudinally of the clutch sleeve.

In proceeding with this invention I have recessed the upper edge of the whorl and provided a collar thereon about the blade, while I have formed nested tubular members tapered at their

upper ends having their lower ends in the recess and with a ferrule about their upper ends. The split tubes are so located that their splits are not in registry and are pinned in this position. By this arrangement a resilient clutch is provided wherein one resilient tube supports and strengthens the other and no dirt can enter within due to the fact that the split portions are not in registry, whereby the clutch will function for a long period of time without fouling.

With reference to the drawing, 10 designates a blade upon which is mounted a whorl 11 having a driving belt receiving portion 12. The long taper of the blade and whorl bore 13 serve as a driving connection between the two. At the upper end of this whorl I provide a recess 14 while a collar 15 extends upwardly beyond the top 16 of the whorl to snugly embrace the spindle blade 10.

20 The clutch consists of a pair of nested tubes one of which is shown in perspective in Fig. 5 and designated generally 17. There is a cylindrical portion 18 of each tube with a frustoconical upper portion 19 formed by drawing the tube inwardly. The tube is split longitudinally throughout its length as at 20. Another similar tube designated 21 is nested within this tube 17 and contacts with it. However, the split or slot 22 thereof, similar to the split or slot 20, is out 25 of registry as shown in Fig. 4. As these tubes contact substantially throughout their outer and inner surfaces, one supports the other and further no dirt can enter into the hollow portion within the nesting tube. In order that these tubes may maintain this relative position, a pin 23 extends through both tubes and through the collar of the whorl to lock all the parts in their relative position against relative rotation. A ferrule 24 having a downwardly extending flange 25 30 fits closely about the blade 10 and acts as a limit to expansion of the clutch members while also assisting in directing the bobbin into position.

The bobbin designated 26, usually of wood, has an upper bore portion 27, an intermediate larger bore 28, and a still larger bore 29. This larger bore may be lined with the metallic sleeve 30 as shown clearly in Figs. 1 and 3. When the bobbin is removed and the clutch is in relaxed position as shown in Fig. 2 the tubular members expand 35 so as to be substantially in contact with the outer periphery of the surface of the groove 14 as well as in contact with the flange 25 of the ferrule 24. As the bore 29 of the bobbin 26 is positioned the tapered portion of the clutch guides the bore and the clutch is compressed so that the inner tubular member 21 will engage the collar 15 and truly align this lower end of the bobbin with the blade at this location while at the upper end of the bobbin the bore 27 will engage the blade 10 and truly align this end of the bobbin with the

blade. Thus by this relationship whereby the clutch engages the collar, the lower end of the bobbin is aligned so that the bobbin will rotate truly with respect to the axis of the blade. In all instances the bottom 32 of the bobbin will engage the upper end 16 of the whorl so as to locate the bobbin vertically that it may receive the traversing yarn in the desired position thereon.

In some cases instead of the tubular sleeves, as shown in Fig. 5, they may be made with a helical slit 33 as shown in Fig 6 at 17', but the sleeves will be otherwise the same both as to the outer sleeve and the inner sleeve which will nest therein.

I claim:

1. In a spindle, a blade, a bobbin clutch comprising a pair of nested resilient split tubes surrounding said blade and out of contact therewith for the entire length of said tubes, said tubes snugly fitting each other and with their split edges out of registry whereby to limit the entry of foreign matter within said tubes.

2. In a spindle, a blade, a bobbin clutch comprising a pair of nested resilient split tubes surrounding said blade and out of contact therewith for the entire length of said tubes, said tubes with their split edges extending helically and out of registry whereby to limit the entry of foreign matter within said tubes.

3. In a spindle, a blade, a bobbin clutch comprising a pair of nested resilient split tubes surrounding said blade and out of contact therewith for the entire length of said tubes, said tubes with their split edges out of registry whereby to limit the entry of foreign matter within said tubes, said tubes having frusto conical upper portions.

4. In a spindle, a blade, a bobbin clutch comprising a pair of nested resilient split tubes surrounding said blade and out of contact therewith for the entire length of said tubes, said tubes with their split edges out of registry whereby to limit the entry of foreign matter within said tubes, and a ferrule about the upper edges of said tubes to limit their expansion.

5. In a spindle, a blade, a bobbin clutch comprising a pair of nested resilient split tubes surrounding said blade and out of contact therewith for the entire length of said tubes, said tubes with their split edges out of registry whereby to limit the entry of foreign matter within said tubes, said tubes having frusto conical upper portions, and a ferrule about the upper edges of said tubes to limit their expansion.

6. In a spindle, a blade, a bobbin clutch comprising a pair of nested resilient split tubes surrounding said blade and out of contact therewith for the entire length of said tubes, said tubes with their split edges out of registry whereby to limit the entry of foreign matter within said tubes, and means to prevent relative rotation of the clutch and blade.

7. In a spindle, a blade, a whorl thereon having a collar at its upper end and a recess about the collar, a bobbin clutch comprising a pair of nested resilient split tubes surrounding said blade and out of contact therewith for the entire length of said tubes, said tubes extending into said recess and surrounding said collar and normally free thereof and adapted to be contracted by the bobbin to cause the inner tube to engage said collar.
